PHOTOGRAPHIC TRIPOD

David I. Welt, Scarsdale, N. Y.

Application September 13, 1955, Serial No. 37,915

Term of patent 14 years

(Cl. D61—1)

Fig. 1 is a front elevational view of a photographic tripod, showing my new design;

Fig. 2 is a fragmentary rear perspective view of the photographic tripod shown in Fig. 1 showing details of the pan head and upper tripod portion;

Fig. 3 is a side elevational view of the pan head, and

Fig. 4 is a front elevational view of the pan head shown in Fig. 1 with the camera mounting portion positioned for vertical mounting.

The tripod has been omitted completely in Figs. 3 and 4 and partially in Fig. 2 for the convenience of illustration only.

I claim:

The ornamental design for a photographic tripod, substantially as shown and described.
